UNITED STATES PATENT OFFICE.

GEORGE B. ROBERTS, OF CHICAGO, ILLINOIS.

FUEL ECONOMIZER.

Application filed June 13, 1925. Serial No. 36,987.

To all whom it may concern:

Be it known that I, GEORGE B. ROBERTS, a citizen of the United States of America, and a resident of Chicago, county of Cook, 5 and State of Illinois, have invented a new and useful Improvement in Fuel Economizers, of which the following is a specification.

This invention relates to those fuel burner attachments which are known as economizers, and is applicable especially to gas ranges and the like. The main objects of the invention are to provide an economizer adapted to reduce the amount of fuel necessary to accomplish a given available heating effect; to enhance the heating effect of a given amount of fuel; to throw the gaseous fuel into a state of violent agitation adjacent to the point of discharge to the burner 10 or burners; to provide in the pathway of the fuel means formed and adapted to produce a spiral whirling movement of the gas; to provide a nozzle-like member of this character with adjusting means adapted to regulate the rate of discharge; to provide in a gas range admitting air to the fuel before it reaches the burner means operable by the flow of gas to agitate and mix the gas and air, and to provide such means of simple 15 and durable form adapted for ready manufacture at low cost and capable of ready application both for new equipments and for old installations.

An illustrative embodiment of this invention is shown by the accompanying drawings, in which:

Fig. 1 is a fragmentary plan of an ordinary gas burning kitchen range showing the right-hand front corner, adjacent to 40 which the attachment embodying this invention is disposed.

Fig. 2 is a greatly enlarged horizontal axial section through the attachment shown at the lower right hand corner of Fig. 1.

Fig. 3 is mainly a cross section on the line 3—3 of Fig. 2.

Fig. 4 is a perspective view of the nozzle and the associated screen as viewed from the front and right of Fig. 2.

Fig. 5 is mainly a horizontal axial section showing a modified construction and arrangement of parts to be used one for each burner outlet, as at E on Figs. 1 and 5, instead of or supplementing the one common economizer shown in Figs. 1 and 2. In this instance there may be a common manual

control valve in the pipe section 2' instead of one for each branch 5, as will be understood.

In the construction shown in the drawings, Figs. 1 to 4, the economizer 1 is constructed in the form of an elbow member inserted in the gaseous supply pipe 2, which supplies the burners, not shown, on the range 3, which burners are fed through the 65 several manual control valves 4.

In order to facilitate understanding of the invention, it may be observed at this point that the operation of the economizer 1 imparts to the incoming fuel, received 70 through the pipe section 2', a high state of agitation as it passes into the section 2'', from which it is delivered through the branch pipes 5 to the burners.

With this in view, the economizer is provided with a fixed coaxial restricting member or nozzle 6 in which is mounted a conical rotary agitator 7. This nozzle 6 is disposed with its wide end toward the source of fuel and with its narrow end extending into the pipe 2''. The base of cone 6 is cylindrical and fits snugly in the pipe 2'' where it is held rigidly by friction. The rotor member 7 is provided with spiral vanes 8 on its conical face whereby the passing fuel reacts to impart rotation, as a result of which the fuel is violently agitated and caused to enter the tube 2'' with a rapid whirling or spiral motion. The elbow member is threaded at 1' and 1'' to admit the 90 pipes 2' and 2'' respectively.

In order to enable the attendant to adjust the agitator 7 and also regulate in a measure the flow of fuel through the nozzle 6, the cone 7 is mounted rotatably on the 95 end of a longitudinally adjustable shaft 9, the adjacent end of which is threaded at 10 to fit in a supporting cross bar 11 at the base of the nozzle 6.

The other end of the bar 9 extends 100 through a threaded removable support 12 at the opposite end or corner of the elbow member and projects, where its slotted end 9' is accessible for adjustment by means of a screw driver, upon removal of the cap 13. 105 The support 12 is made in sections so as to provide for packing 14. A screen 15 is disposed across the base of said cone 6 as will be understood. The ends of bar 11 and the rim of screen 15 are secured to the base of 110 cone 6, as by means of solder.

In operation, when a burner is started the

rush of gas past the rotor 7 causes it to spin on its axis. If a choking effect is desired at this point, the screw 9 is turned clockwise, that is to say, inwardly and vice versa.

5 I have experimented extensively with kindred devices and have caused a thorough test to be made of this device on a standard gas stove, mainly to determine the volume of gas passed through the pipe to a burner 10 first without the device and then with it. The temperature was taken as to the heat generated with and without this economizer. Accurate record was kept as to time, volume of gas and the temperature, with and without 15 the device. The economy shown was substantial and most satisfactory.

Referring to the embodiment shown in Fig. 5, the economizer here referred to by numeral 21 is attached to the individual 20 burner tube 5 at its junction, with the main supply tube 2". In this instance, the guide cone 21, rotor 22, adjusting screw 23, packing 24, and packing holder 25 are substantially similar to the corresponding parts 25 respectively shown in Fig. 2, and function in substantially the same way, but in this instance the economizer is individual to the corresponding burner instead of being common to a plurality of burners. Moreover, 30 in this instance the tube 5 is provided with a plurality of small air inlet openings 26, adjacent to the discharge tip of the guide cone 21, whereby air becomes thoroughly mixed with the whirling fuel so that when 35 the air and gas mixture reaches the burner it is in a state of agitation and is thoroughly mixed.

In attaching this economizer to old installations, or to new ranges made up without any economizer, it may be noted that there is always a supply pipe that comes in from the gas main, and connected to the pipe is an L at the corner or front of the stove. Usually the size of the original pipe 40 is about $\frac{3}{4}$ of an inch for supplying gas to six burners in front of the stove.

45 In installing this device I disconnect the L originally there and insert the economizer L in place of it, which is the same size. By reason of the adjustment feature I can reduce the volume of gas and increase the pressure because the pipe size back of it is much larger than the adjustment aperture which it passes through. I have found that 50 a great deal of gas is wasted for lack of proper combustion, and I attribute that to lack of gas agitation or mixture of the gas with the air. This device being restricted at the point 6 gives additional force as the 55 gas passes out. That creates a commotion in the gas as it passes through and into the

60 pipe 2" and comes into contact with the direct supply for each burner. This device causes a thorough mixture of gas and air, so that every particle of gas is utilized and 65 consumed. Another advantage of the adjustability feature is that in the event of the pressure getting very low, the screw 9 and agitator 7 may be drawn back and so give a larger supply of gas, according to 70 how far the screw is turned back.

75 Although only two specific embodiments of this invention are herein shown and described, it is to be understood that no attempt has been made to show all practical embodiments, and that some of the details of the constructions shown and described may be altered or omitted without departing from the spirit of this invention as defined by the following claims.

80 I claim:

1. A fuel economizer comprising a tubular member through which the fuel is conducted, said member having a turbine reaction rotor mounted therein adapted for 85 actuation by the flow of fuel, and said member having a lateral aperture and sealing means therefor, with a screw member mounted therein for adjustment of said 90 rotor to more or less restrict the fuel passageway, according to the setting of said screw member.

2. A fuel economizer comprising a tubular member through which the fuel is conducted, said member having a reaction rotor 95 mounted therein adapted for actuation by the flow of fuel, and said member having a lateral aperture and sealing means therefor, with a screw mounted therein for adjustment of said rotor to more or less restrict the fuel passageway, according to the setting of the screw, said member having a 100 restricted portion adjacent to said rotor and a cross member adjacent thereto with a threaded aperture for said screw.

105 3. A fuel economizer comprising a tubular member through which the fuel passes, said member having restricting means and a rotary reaction agitator adjacent thereto, whereby the passage of fuel past said agitator rotates the same and thereby throws the fuel into spiral movement and causes its thorough agitation, said rotor having a 110 fixed supporting shaft on one end of which it is mounted, which shaft is threaded for 115 adjustment and projects through a snug aperture in the wall of said member for access.

Signed at Chicago this 2nd day of June 1925.

GEORGE B. ROBERTS.
